UNITED STATES PATENT OFFICE

JAMES E. HOWARD, OF JEFFERSONVILLE, INDIANA

VESSEL CONSTRUCTION

Application filed September 20, 1930. Serial No. 483,216.

This invention relates to a novel vessel construction and the provision of means in such construction for preventing ice and floating débris from passing under the vessel and thereby causing a harmful effect on the propelling means thereof.

One of the objects of this invention is to provide a novel bow construction for barges and vessels of like character.

Another object of this invention is to provide a flat bottom vessel of such construction that as it advances through the water, ice and floating débris encountered at the bow of the vessel, is directed away from the sides of the vessel and prevented from travelling along beneath the bottom plate under the vessel, thereby impeding the propulsion thereof, and endangering the propelling devices where such devices are used.

A still further object of this invention is to provide a flat bottom boat structure having features of construction to produce a boat of rugged and compact nature and adapted to efficient propulsion.

Various other objects will appear more fully hereinafter, all of which objects are obtainable by a construction of the type illustrated in the accompanying drawing, in which,

Figure 1 is a bottom plan view of my novel vessel construction;

Fig. 2 is a view in side elevation; and

Fig. 3 is an end view of the bow portion.

Fig. 4 is a sectional view taken along the line 4—4 in Fig. 1;

Fig. 5 is a sectional view taken along the line 5—5 in Fig. 1;

Fig. 6 is a sectional view taken along the line 6—6 in Fig. 1.

This invention resides substantially in the construction, combination, arrangement and relative location of parts all as will be more fully pointed out hereinafter.

Heretofore difficulty has been encountered in the use of vessels of the scow or barge type by reason of ice or floating débris passing along under and in contact with the bottom surface of such vessel thereby impeding the propulsion thereof and endangering the propellers or the other propulsion devices with

which such ice or débris may come in contact. The invention hereinafter disclosed for avoiding the just mentioned undesirable effects, while adaptable to any boat or vessel having a flat top and bottom is of particular value 55 when utilized in the scow or barge type of boat and, therefore, will be described in such connection. The employment of a sharp prow in the construction of the bow portion of the vessel while lending itself to increased 60 efficiency of propulsion, and while inherently tending to direct floating débris away from the sides and from beneath the bottom of the vessel lacks the advantage that is to be found in vessels of uniform flat top and bottom 65 plate type, namely the advantage of increased storage space and buoyancy.

I have found that the desirable effects of a prow similar to that used in the type of boat commonly known as the model boat, 70 when combined with a bow portion of the type used in a boat of the scow class, gives a vessel structure having the combined advantages above pointed out as being desirable as well as the advantage residing in the inherent 75 tendency of the bow portion when formed with a cut water edge to maintain the vessel on its course.

Referring now to the drawing it will be seen that the boat 1, substantially rectangular in conformation (see Fig. 6), is formed with a stern portion 2 preferably of the over-hanging type to permit of the proper mounting, securing and working of propulsion devices. The bow portion of such boat is indicated 80 generally at 3 and is formed by the union of two different types of bow structures, namely a bow portion 4 of the type commonly known as the bow portion of a model boat and a second bow portion 5 of a type commonly known as the bow portion of a scow. The top plate 6 of the boat 1 is uniformly flat throughout and substantially of rectangular form while the bottom plate 7 of the boat 80 although substantially flat over the major portion thereof is, at the stern end 2, deflected so as to form an overhanging stern. At the bow end this horizontal under or bottom plate 7 is formed with forwardly curved edges 8 which converge toward each other to 100

the vertical line of the prow 9, where they meet. Rising up from the bottom plate all along the curved edges 8, are the correspondingly curved side plates 10, going to make up the bow portion 4.

Depending from the forward edge of top plate 6 is the flat transversely extending end plate 11 having edges 12-12. This end plate is formed so that the prow line 9 joins therewith at substantially its midlength point. Extending rearwardly from the end plate 11 along the edges 12, 12 are the curved scow boat plate portions 5, which merge rearwardly together with the curved plates 10 of the model bow portion 4 into the usual flat sides 13. It will be noted from an inspection of Figs. 2 to 6 inclusive that the curved plate portions 5 are shown as convex with regard to elements 10 and 11.

By thus combining the flat, upturned or curved scow bow portion with the model bow portion a combined novel bow portion is created, the advantages of which are that the prow of the model bow portion tends to lend efficiency of propulsion to the vessel and also to deflect from under the boat any ice or floating débris, which, ordinarily would pass along the bottom thereof while at the same time the features of a substantially flat scow top and bottom surfaces is retained, and hence there is no substantial loss of deck space or carrying capacity.

It is to be understood that the vessel structure shown as embodying my invention is but one of many possible embodiments readily adaptable to accomplish the objects hereinbefore set forth. It also will be apparent that those skilled in the art may readily conceive of various other possible embodiments and combinations of structure therefor, and hence, while I have shown and described a specific embodiment of my invention, I do not desire to be limited thereby but rather by the scope thereof as defined in the appended claims.

What I claim therefore as new and useful and desire to secure by United States Letters Patent is:

1. A vessel having a bow construction combining a bow portion of the model boat type and a bow portion of the scow type terminating in a transversely extending bow end plate.

2. A vessel having a uniformly flat and substantially rectangular deck, and a bottom substantially flat over the major portion thereof and vertical sides having plane parallel upper bow portions and lower bow portions longitudinally curved toward each other at their forward ends.

3. A vessel having a substantially flat bottom plate, a top, a transversely extending bow end joined to said top, and vertical sides curved longitudinally at the bow to meet said end plate at its midlength and form-

ing a fore-and-aft curved surface to deflect floating matter and débris away from the vessel at the sides thereof.

4. A vessel having a substantially flat bottom, a top, a transversely extending bow end plate joined to said top, and vertical sides curved longitudinally at the bow to meet said end plate at its midlength and forming a fore-and-aft curved surface to deflect floating matter and débris away from the vessel thereof, the forward ends of said sides meeting in a substantially vertical line to form a cut-water edge and to aid in keeping the vessel on its course.

5. A vessel having a substantially flat bottom, a top, a transversely extending bow end plate connected to the top, and vertical sides at the bow arranged to meet said end plate at its midlength to form a fore-and-aft deflecting surface to deflect floating matter and débris away from said vessel at the sides thereof.

6. A boat of the type described having an overhanging stern portion adaptable to house propellers or the like, a top, sides, a bottom adapted, due to its conformation to form the over-hanging stern portion, a combination bow comprising a transversely extending flat plate and a cutwater edge joined to said plate at the midpoint along its lower edge to provide a bow portion having a conformation adapted to deflect floating débris from travelling along the bottom and entering the over-hanging stern portion.

7. A structure recited in claim 6 characterized in that the bow portion construction includes a model boat bow portion and a scow bow portion.

In testimony whereof I have hereunto set my hand on this 16th day of September, A. D. 1930.

JAMES E. HOWARD.
